LATCH HANDLE

Ulysses L. Thomas, Detroit, Mich., assignor to
 Chrysler Corporation, Highland Park, Mich., a
 corporation of Delaware

Application November 14, 1941, Serial No. 419,069

3 Claims. (Cl. 292—347)

The present invention relates to a latch handle for an automobile door or the like. The object of the present invention is to form a latch handle of sturdy construction from sheet material, thereby saving die casting metal which has greater utility in other applications. The present invention permits the use of a much smaller amount of metal in the construction of door handles than has been heretofore thought possible.

The objects and advantages of the present invention will be more readily ascertainable from an inspection of the following specification taken in connection with the accompanying drawing wherein like numerals refer to like parts throughout.

In the drawing, Fig. 1 is a perspective view of an automobile having a door handle of the present invention associated therewith;

Fig. 2 is an enlarged plan view of the door handle of the present invention taken substantially along line 2—2 of Fig. 1;

Fig. 3 is an elevational view of the door handle of the present invention;

Fig. 4 is a longitudinal sectional view through one of the members forming the door handle;

Fig. 5 is a longitudinal sectional view through the complementary door handle forming member and associated parts;

Fig. 6 is a perspective view on an enlarged scale taken substantially along line 6—6 of Fig. 5;

Fig. 7 is a sectional view taken substantially along line 7—7 of Fig. 2; and,

Fig. 8 is a sectional view taken substantially along line 8—8 of Fig. 2.

The door handle of the present invention is generally designated by the numeral 10 in Fig. 1 and comprises inner and outer channel members 11 and 12, respectively. The inner channel member 11 has its web portion 13 extended angularly outward close to each end to meet the outer edges of the flanges 14, the outwardly extending portions thus forming a tip end wall 15 and a base end wall 16. The base end wall 16 is of relatively large extent and is provided with a tongue 17 extending beyond the flanges 14 and raised slightly from the plane of the base. The outer channel member 12 has inwardly extending flanges 20 so shaped as to embrace the flanges 14 of the inner channel member, and its web portion 21 is provided with protruding tangs 22 and 23. The tangs are adapted to be engaged about the end walls of the inner channel member as shown in Figs. 2, 3, and 8, thereby locking the channel members in assembled relation, in

which assembled relation the channel members form a tubular operating lever.

The end wall 16, which is of relatively large extent, is fastened to the surface of a trim piece 30 adapted to bear against the bearing rib 31 of an escutcheon plate 32, or similar bearing surfaces. Both the end wall 16 and the trim plate 30 are pierced to receive the rectangular end of a latch operating lever 33, the inner end 10 of which is fastened to the flanges 14 of the inner channel member 11 as by means of spot welds 34. The end wall 16 is likewise fastened to the trim piece 30 as by means of spot welds 35. The raised tongue 17 permits insertion of the tang 22, which may be preset in the position shown in Fig. 4, between the surfaces of the end wall and the trim plate. Thereafter, the other tang 23 may be bent around the other end wall 15.

20 The convenient sheet metal parts of the improved handle can be conveniently finished by plating, painting, or in any suitable manner while they are disassembled and thereafter assembled, the particular attaching means by which they are held together being so constructed and arranged as to avoid injuring the finish applied prior to assembly.

Having described a preferred embodiment of 30 the present invention, it should be apparent to those skilled in the art that the same permits of modifications in arrangement and detail. All such modifications as come within the scope of the following claims are considered to be a part 35 of my invention.

I claim:

1. A latch handle for an automobile door or the like comprising an inner channel member having a web and substantially parallel flanges 40 extending substantially at right angles to the plane of the web, the ends of the web being extended angularly outward close to each end to meet the outer edges of the flanges, the angularly extended portions thus forming a tip end 45 wall and a base end wall, and a complementary outer channel member having side flanges shaped to embrace the flanges of the inner channel member whereby said channel members together form a tubular operating lever, the free edge 50 portions of the side flanges of said outer channel member being disposed in planes substantially parallel to the registering side flange portions of said inner channel member and terminating between the lateral extremities of the latter side flanges said outer channel member having pro-

truding tangs at each end of its web adapted to be engaged about said end walls of said inner channel member to lock the channel members in assembled relation.

2. A latch handle for an automobile door or the like comprising an inner channel member having a web and substantially parallel flanges extending substantially at right angles to the plane of the web, the ends of the web being extended angularly outward close to each end to meet the outer edges of the flanges, the angularly extended portions thus forming a tip end wall and a base end wall, a complementary outer channel member having its flanges shaped to embrace the flanges of the inner channel member whereby said channel members together form a tubular operating lever, said outer channel member having protruding tangs at each end of its web adapted to be engaged about said end walls of said inner channel member to lock the channel members in assembled relation, said base end wall being of relatively large extent and having an opening therethrough, and a latch operating rod extending through said opening and having its end portion fixed to the flanges of said inner channel member.

3. A latch handle for an automobile door or the like comprising an inner channel member

having a web and substantially parallel flanges extending substantially at right angles to the plane of the web, the ends of the web being extended angularly outward close to each end to meet the outer edges of the flanges, the angularly extended portions thus forming a tip end wall and a base end wall, a complementary outer channel member having its flanges shaped to embrace the flanges of the inner channel member whereby said channel members together form a tubular operating lever, said outer channel member having protruding tangs at each end of its web adapted to be engaged about said end walls of said inner channel member to lock the channel members in assembled relation, said base end wall being of relatively large extent and having an opening therethrough, a latch operating rod extending through said opening and having its end portion fixed to the flanges of said inner channel member, and a trim plate, through which said operating rod extends, fixed to the surface of said base end wall, the tip of said base end wall being raised from the surface of the trim plate adjacent thereto in order to permit the insertion of the tang of the outer channel member associated therewith between said end wall and said trim plate.

ULYSSES L. THOMAS.
